UNITED STATES PATENT OFFICE

2,309,216

GAME APPARATUS

Edward Rouskie, New York, N. Y.

Application December 6, 1940, Serial No. 368,835

4 Claims. (Cl. 272—31)

This invention relates to game apparatus. It is particularly directed to a game of skill which creates an illusion of driving one or more automobiles on a race track, or a ship sailing through a mine or submarine infested sea, or moving any other object through a field, and is generally an improvement of the structure shown in my Patent No. 2,108,726, issued February 15, 1938.

An object of this invention is to provide a game of the character described including an electric motor operated rotary disc carrying electrical contacts, and means operated individually by a pair of contestants to control the position of a pair of objects on the disc as the disc rotates, and electric means to record the number of contacts made by each of said objects with the electric contacts on the disc.

A further object of this invention is to provide in a game of the character described, a rotary disc having a non-annular path marked thereon, and means controlled by a player to retain an object on said path as the disc rotates, and means to count the number of revolutions of the disc while the object is kept on the path and the number of times the object moves off the path onto another part of the disc.

A still further object of this invention is to provide game apparatus of the character described, in which each player controls the movement of an article eccentrically pivoted and mounted on a rotating disc, and means to record the degree of skill with which the article is controlled as the disc rotates, means being further provided to manually operate the recording device to bring it to a predetermined position at which to start the game.

Yet a further object of this invention is to provide a simple, rugged and durable game apparatus of the character described, which shall be relatively inexpensive to manufacture, which shall test the skill of the players, and which shall be amusing and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a top plan view of apparatus embodying the invention;

Fig. 1a is a cross-sectional view taken on line 10a—10a of Fig. 1;

Fig. 2 is a wiring diagram illustrating the recording and motor operated mechanism for the apparatus shown in Fig. 1;

Fig. 3 is a view similar to Fig. 1, but showing the position of the vehicle simulating member on the track simulating path of the disc;

Fig. 4 is a wiring diagram, similar to Fig. 3, but illustrating the position of the parts after the automobile has contacted the conductor which traverses the track simulating portion of the disc;

Fig. 5 is a side elevational view of the automobile simulating member shown in Figs. 1 and 3; and

Fig. 6 is a bottom plan view thereof.

Referring to Figs. 1 to 6 there is disclosed game apparatus 10c, embodying the invention. The apparatus 10c is played by a single player and includes a turntable or disc 122 rotated in any suitable manner by mechanism such as disclosed in my Patent No. 2,108,726 driven by motor 160 instead of manually as shown in said patent. The apparatus 10c also includes operating mechanism to control movement of a vehicle simulating member 58c, similar to the control mechanism of said Patent No. 2,108,726. The disc 122 has on its upper surfaces a track portion 123 of insulating material, a central portion 124 of conducting material and an area 125 surrounding the track, likewise of conducting material. On the track 123 is a transverse strip 126 of conducting material, insulated from the areas 124 and 125.

On the underside of the disc 122 are two concentric conductor rings 127 and 128. The outer ring 128 is connected by suitable conductors 129 to the conductor areas 124, 125, whereas the inner ring 127 is connected by a conductor 130 to the transverse conductor strip 126. On the underside of the disc are two brushes 131 and 132, the former in engagement with the ring 128 and the latter in engagement with the ring 127.

The purpose of the player is to manoeuvre the vehicle simulating member 58c so as to keep it on the track 123. Member 58c has a brush 60c on the underside thereof, adapted to be in electrical engagement with the control rod 50.

Means is provided to count the number of times the brush 60c contacts the transverse con-

ductor 126, and thus, to count the number of laps which the car makes on the track 123.

Means is also provided, as will be explained hereinafter, to keep a record of the number of times that the brush 60c moves either onto the conductor areas 124 or 125, thus getting off the track, such count being known as "errors." To this end, the top wall 25c of the apparatus 10c has two openings 134 and 135. Printed above the opening 134 is the word "errors," and above the opening 135 is the word "laps." Mounted on shafts 136 and 137 within the apparatus, are counter wheels 136a and 137a, the top portions of which may be seen through the openings 134 and 135. The peripheries of the wheels are numbered from zero to 10. Mounted on the shafts 136 and 137 and fixed to the wheels 136a and 137a are ratchet wheels 136b and 137b. The ratchet wheels are prevented from moving in one direction by springs 136c and 137c. Fixed to ratchet wheel 137b, is a collar 138 provided with a radial tooth or projection 139 aligned with the zero on the counter wheel 137a.

Fixed within the apparatus are a pair of switches 140 and 141 in contact with one another, but adapted to be moved out of contact by projection 139 on the collar 138 when the counter wheel 137 shows a zero at the top through the opening 135. When the counter wheel is moved away from zero position, the switch arms 140 and 141 contact each other.

To operate the ratchet wheel 137b, there is provided a solenoid 143, one side of which is connected by wire 144 to brush 132. The other side of the solenoid is connected by wire 145 to switch arm 141. The ratchet wheel 136b is operated by a solenoid 147, one side of which is connected by wire 148 to the switch arm 140. The other side of the solenoid is connected by wire 150 to the brush 131. The control rod 50 is electrically connected by wire 151 to one terminal 152 of a battery 153. The other terminal 154 of said battery is connected by wire 155 to the wire 145 and hence to one side of the solenoid 143 and to the switch arm 141. The operating motor 160 has one side thereof connected to the battery terminal 154 and the other through the rheostat 161 to the other battery terminal 152.

The operation of the apparatus 10c will now be described:

Normally the parts are in a position shown in Fig. 2, with the switches 140 and 141 open. When the brush 60c of member 58c contacts conductor 126, a circuit is completed through solenoid 143 to rotate ratchet wheel 137b and hence counter wheel 137a to bring number 1 to view. Until that is done solenoid 147 cannot be energized because the switch 140, 141 would be open. After one lap is registered, then each time the brush on member 58c contacts conducting strip 126, the counter wheel 137a will register an additional lap, and each time said member contacts either of the two conducting areas 124, 125, solenoid 147 will be energized to register an error.

At the completion of a predetermined number of laps projection 139 on the collar 138 will disengage switches 140 and 141 thereby breaking the circuit to solenoid 147 thus denoting the end of the game.

Extending into conducting field 124 there are provided several small strips of insulating material 123a, the purpose of which is to make and break the circuit to the solenoid registering errors, should the vehicle simulating member 58c

get on to the conducting field 124 and remain thereon.

It will thus be seen that there is provided a device in which the several objects of this invention are achieved, and which is well adapted to meet the conditions of practical use.

As various possible embodiments might be made of the above invention, it is to be understood that all matter herein set forth or shown in the accompanying drawings is to be interpreted as illustrative and not in a limiting sense.

Having thus described my invention, I claim as new and desire to secure by Letters Patent:

1. Apparatus of the character described, comprising a turntable, means to rotate the turntable, a non-circular track on the turntable, a vehicle simulating member on the turntable, manual means to control the position of the vehicle simulating member on the turntable, as the turntable rotates, means to record the number of laps which the vehicle simulating member remains on the track, as the turntable rotates, means to record the number of times the vehicle simulating member gets off the track, and means to prevent the second recording means from operating until one lap is recorded on the first recording means.

2. Apparatus of the character described, comprising a turntable, means to rotate the turntable, a non-circular track on the turntable, a vehicle simulating member on the turntable, manual means to control the position of the vehicle simulating member on the turntable, as the turntable rotates, and means to record the number of laps which the vehicle simulating member remains on the track, as the turntable rotates, said lap recording means, including means to control operation of the means to record the number of times the vehicle gets off the track.

3. Apparatus of the character described, comprising a turntable, means to rotate the turntable, a non-circular track on the turntable, a vehicle simulating member on the turntable, manual means to control the position of the vehicle simulating member on the turntable, as the turntable rotates, means to record the number of laps which the vehicle simulating member remains on the track, as the turntable rotates, means to record the number of times the vehicle simulating member gets off the track, and means to prevent the second recording means from operating until one lap is recorded on the first recording means, said preventing means also serving to stop operation of said second recording means when said lap recording means records a predetermined number of laps.

4. Apparatus of the character described, comprising a turntable, means to rotate the turntable, a non-circular track on the turntable, a vehicle simulating member on the turntable, manual means to control the position of the vehicle simulating member on the turntable, as the turntable rotates, means to record the number of laps which the vehicle simulating member remains on the track, as the turntable rotates, and means to record the number of times the vehicle simulating member gets off the track, said last means including a conducting portion on the turntable, outside of the track, and non-conducting portions projecting into said conducting portion.

EDWARD ROCUSKIE.
